US0D1028756S

(12) **United States Design Patent** (10) **Patent No.:** **US D1,028,756 S**
(45) **Date of Patent:** **** May 28, 2024**

(54) **TAPE MEASURE**

(71) Applicant: **Sichuan Qianli-beoka Medical Technology Inc.**, Sichuan (CN)

(72) Inventor: **Wen Zhang**, Chengdu (CN)

(73) Assignee: **Sichuan Qianli-beoka Medical Technology Inc.** (CN)

(**) Term: **15 Years**

(21) Appl. No.: **29/812,087**

(22) Filed: **Oct. 19, 2021**

(30) **Foreign Application Priority Data**

Apr. 19, 2021 (CN) 202130223636.3

(57) **CLAIM**

The ornamental design for a tape measure, as shown and described.

DESCRIPTION

FIG. 1 is a front perspective view of the tape measure showing my new design;

FIG. 2 is a front elevational view thereof;

FIG. 3 is a back elevational view thereof;

FIG. 4 is a right elevational view thereof;

FIG. 5 is a left elevational view thereof;

FIG. 6 is a top plan view thereof; and,

FIG. 7 is a bottom plan view thereof.

1 Claim, 7 Drawing Sheets
